UNITED STATES PATENT OFFICE.

GEORGE B. KELLY, OF JAMAICA PLAIN, AND FREDERICK L. WOOD, OF WORCESTER, MASSACHUSETTS, ASSIGNORS TO AEOLIAN COMPANY, A CORPORATION OF CONNECTICUT.

PLAYING ATTACHMENT FOR MUSICAL INSTRUMENTS.

No. 902,663.

Specification of Letters Patent.

Patented Nov. 3, 1908.

Application filed November 21, 1907. Serial No. 403,206.

To all whom it may concern:

Be it known that we, GEORGE B. KELLY and FREDERICK L. Wood, citizens of the United States, and residents of Jamaica Plain, Suffolk county, State of Massachusetts, and Worcester, in the county of Worcester and State of Massachusetts, respectively, have invented certain new and useful Improvements in Playing Attachments for Musical Instruments, of which the following is a specification.

This invention relates to improvements in playing attachments for musical instruments, in which a note sheet is wound from a music roll and upon a take up roll and after the piece has been played, is rewound from the take up roll upon the music roll, which rolls are connected with a gear or mechanism for rotating either of said rolls from a motor and are also provided with means for adjusting the said rolls so as to bring the lines of perforations on the music sheet in proper alinement with ducts in a tracker board over which the sheet is drawn.

The object of our invention is to provide a new and improved frame or structure in which the shafts for the rolls, the means for adjusting the rolls lengthwise and the winding and rewinding gear are all contained in a structure as an entirety so that this structure as an entirety can be placed into and secured in the playing attachment or machine without requiring any adjustment of parts or attaching of parts after this structure as an entirety, has been secured in the instrument.

In the accompanying drawings, in which like letters of reference indicate like parts in all the figures:—Figure 1 is a vertical sectional view of our improved frame and the winding, adjusting and motor gear mounted therein, parts being shown in elevation and others broken away. Fig. 2 is a side view of the same, parts being in section and others broken away and others omitted. Fig. 3 is a plan view of part of the same.

The frame is composed of two side pieces 1 and 2, united by cross bolts 3. In the top part of the frame a horizontal shaft 4 is mounted in bushings 5 in the side plates 1 and 2, one end 6 of said shaft being forked or otherwise shaped to receive a pin or projection on one end of a music roll. The right hand end of this shaft is shaped as a

step 7 which bears against a step bearing 8 mounted in said bushing to move lengthwise of the shaft 4 which step bearing can be adjusted by a screw 9 bearing against the outer end of the stem 10 of said step bearing, said screw being screwed through an arm 19 of a rock shaft 11 mounted in curved brackets 12 projecting from the outer side of the said plate 2. The lower shaft 13, for the take up roll, is also provided with a forked end, or equivalent structure for receiving a projection on one end of the take up roll, and this shaft 13 is mounted in the bushings 14, the right hand end of said shaft 13 also bearing against a step bearing 15, a movable in the bushings 14 and having a stem 16 against the outer end of which a screw 17 rests which is screwed through the arm 18 on the lower end of the rock shaft 11. The rock shaft 11 is provided with an arm 20 the outer end of which is connected with a manipulating link 21 by means of which the rock shaft can be rocked and thus the arms 18 and 19 of this rock shaft moved in the direction toward or from the side wall 2.

When the arms 18 and 19 are swung toward the side wall 2 both shafts 4 and 13 are moved to the left, Fig. 1, but when these arms 18 and 19 are swung from the side wall 2, they permit the music rolls to be forced to the right by the springs usually provided in instruments of this kind, to press on those bearings for the rolls opposite the bearings 6 and which springs are not shown as they form no part of the present invention, and the rolls exerting a pressure on the shafts 4 and 13 move them in the direction toward the right, Fig. 1, as far as the stop screws 9 and 17 in the arms 18 and 19 respectively, will permit. Both shafts 4 and 13 can thus be adjusted longitudinally at the same time.

A cog wheel 22 is fixed on the shaft 13 and can be engaged by a pinion 23 mounted on a shaft 24 to turn with said shaft and move lengthwise on said shaft which shaft 24 carries a sprocket wheel 25, which is rotated by means of a sprocket chain 26 from a suitable motor. The pinion 23 is connected with a clutch 27 which, with the pinion, can be shifted by means of a lever 28, pivoted at 29 and the upper end of which lever engages said clutch 27. A link 30 serves for shifting the lever 28 from some other part of the instrument. A sprocket wheel 31 is

mounted loosely on the shaft 24 and over this sprocket wheel 31 a sprocket chain 32 passes which also passes over a sprocket wheel 33 fixed on the shaft 4. The clutch 27 is provided with a pin 40 and the loose sprocket wheel 31 is provided with the clutch pin 41. When the motor of the instrument is operated the shaft 24 is constantly rotated in the same direction and when the pinion 23 is engaged with the cog wheel 22 the lower shaft 13 is rotated but the upper shaft 4 is not rotated as the sprocket 31 is loose on the shaft 24. With the parts engaged as shown in Fig. 1, the note sheet is being unwound from the roll on the upper shaft 4 upon the roll on the lower shaft 13. When the direction of movement of the paper is to be reversed, the clutch 27 is so shifted as to disengage the pinion 23 from the cog wheel 22 and as to bring the clutch pin 40 in engagement with the clutch pin 41 on the loose sprocket wheel 31 so that the latter is rotated and motion is transmitted by means of the sprocket chain 32 and sprocket wheel 33 and the upper shaft 4 which is rotated in the reverse order at high speed and the sheet wound upon the music or upper roll. It will be seen that the two shafts 4 and 13 as well as the driving gear for the same and the reverse gear and the means for adjusting the shafts longitudinally are all mounted on the frame composed of the two side plates 1 and 2 and the bolts 3 so that this entire mechanism as an entirety can be secured in the instruments without requiring any further adjustment or fastening or mounting of parts.

Having described our invention what we claim as new and desire to secure by Letters 40 Patent is:—

1. A playing attachment for that class of musical instruments making use of a perforated music sheet and two rolls for winding and rewinding the sheet, having a frame 45 containing two rotative music roll shafts which are the only music roll shafts carried by the said frame and which shafts are mounted in said frame, gearing for rotating the shafts which gearing is also mounted in 50 the frame, which frame, with the parts contained therein, is attached as an entirety to the casing of the instrument, whereby the parts carried with the frame have no other connection with the instrument, substantially as set forth.

2. A playing attachment for that class of musical instruments making use of a perforated music sheet and two rolls for winding and rewinding the sheet having a frame 60 containing two rotative music roll shafts which are the only music roll shafts supported on said frame and which are mounted in the frame, means for reversing the direction of rotation of said shafts which means 65 are also mounted in their frame and which

frame with parts therein, is attached as an entirety to the casing of the instrument whereby all parts carried by the frame have no other connection with the instrument, substantially as set forth.

3. A playing attachment for that class of musical instruments making use of a perforated music sheet, and two rolls for winding and rewinding the sheet, having a frame 70 containing two rotative music roll shafts which are mounted in said frame and gearing for rotating the shafts and means for shifting the shafts longitudinally all mounted on said frame, which frame, with the parts contained therein, is attached as an entirety to the casing of the instrument, whereby the parts are not attached individually to the casing of the instrument but are mounted in this frame only, substantially as set forth.

4. A playing attachment for that class of musical instruments making use of a perforated music sheet and two rolls for winding and rewinding the sheet, having a frame 75 containing two music roll shafts which are mounted in the frame and which shafts are longitudinally movable in the bearings in said frame and means for shifting the shafts longitudinally in their bearings which means are also mounted in the said frame, which 80 frame, with the parts contained therein, is attached as an entirety to the casing of the instrument, whereby the parts are not attached individually to the casing of the instrument but are mounted in this frame only, substantially as set forth.

5. A playing attachment for that class of musical instruments making use of a perforated music sheet and two rolls for winding and rewinding the sheet, having a frame 90 containing two rotative and longitudinally movable music roll shafts which are mounted in said frame, means for rotating said shafts, which means are also mounted in said frame, a rock shaft mounted on said frame, arms 95 on said rock shaft for shifting the rotative shafts and means for operating the rock shaft, all of which parts are mounted on said frame, which frame, with the parts contained therein, is attached as an entirety to the casing of the instrument whereby the parts are not attached individually to the casing of the instrument, but are mounted in this frame only, substantially as set forth.

6. A playing attachment for that class of musical instruments making use of a perforated music sheet and two rolls for winding and rewinding the sheet, having a frame 105 containing two rotative and longitudinally movable music roll shafts, which are mounted in said frame, means for shifting said shafts longitudinally, a driven driving shaft mounted in said frame, means for rotating the rotative music roll shafts from the driving shaft and means for reversing the direc- 110 115 120 125 130

tion of rotation of the said shafts, all of which parts are mounted in the said frame, which frame, with the parts contained therein, is attached as an entirety to the casing of the instrument whereby the parts are not attached individually to the casing of the instrument but are mounted in this frame only, substantially as set forth.

Signed at Worcester in the county of Worcester and State of Massachusetts this 10th day of November, A. D. 1907.
